PROCESS OF MAKING FELT HATS

Samuel Kanner, Providence, R. I.

Application February 10, 1936, Serial No. 63,238

5 Claims. (Cl. 223—13)

The generally approved and popular process in the forming and shaping of felt hats from the formed and dyed bodies, consists in a number of successive steps or operations involving the use of a number of different machines for performing these operations as well as the employment of a number of craftsmen necessary for the proper performance of these several steps.

Briefly, the present day process consists in first manually fitting the unshaped and dyed body to a wooden block of proper size and configuration, the size depending, of course, upon the size the hat is to assume when completed. In fitting the body to the block, the rim portion of the body is turned outwardly and a cord is usually passed tightly and tied around the body at the juncture of the rim therewith, whereupon the block is inverted and applied to a press, being suspended therein by clamps which attach to the body rim. Thus positioned in the press, steam under pressure is admitted to the entire exterior surface of the body until a relatively high degree of saturation occurs.

A plunger then descends and forces the block further into the crown while still subjected to steam under pressure, causing the body to accurately conform to the size and shape of the block. Upon removal of the plunger, the block with the body thus treated is withdrawn from the mold and is applied to a machine which irons the crown smoothly upon the block in an effort to return the fibers of the body to their original condition. Moisture is applied in this ironing step. After the crown has been ironed, the block with the body thereon is applied to a brim ironer where the same treatment is carried out. After both crown and brim have been ironed, pouncing is required where a smooth finish is desired. The pouncing operation necessitates separate machines, one in which the crown is pounced, while the other is employed for brim pouncing. In some instances the steam and moisture treatment has been found to disturb the dye in the body, whereupon special treatment and further hand pouncing for both crown and brim becomes necessary.

After the body has been thus formed, shaped and set, the brim is cut, the lining and sweat bands are applied, the rim is trimmed and the hat is ready for use.

There are several objections to this process, among which are that uniform sizes are not assured, uniform colors are by no means certain, the expense of special machinery and labor necessary in the performance of the many treat-

ments or steps required for the production of a salable article, and the time necessarily consumed in carrying out these several operations.

An analysis of this process discloses that the use of wooden blocks as forms for the hat body, accounts for variations in hat sizes, because of the relatively high coefficient of expansion of wood. The initial steam treatment disturbs and loosens the fabric of the hat body to such extent that several of the subsequent operations are required to restore the fur to its original condition. The steam and saturation treatment is also responsible for color defects, requiring skillful pouncing to restore the body to its original shade and to eliminate blemishes.

The process of my invention eliminates the use of blocks or forms, dispenses entirely with steam and saturation at any stage, obviates the use of ironing and pouncing machines for both crown and brim, and largely does away with hand treatments except in instances where defective hat bodies are encountered.

The drawing forming a part of this description illustrates in a more or less diagrammatic manner the machinery necessary in successfully carrying out the process, and it will be understood that no claim is made to the specific machinery illustrated, but that variations therein may be resorted to without departing from the spirit of the invention.

In the drawing:

Figure 1 is a view showing the first step of the process, that is, applying a coat of vapor to the interior of the hat body,

Figure 2 discloses the second step, the body being applied to the mold and the plunger ready to descend,

Figure 3 illustrates the third step, that is, the plunger has descended and pressure has been applied to the interior of the flexible bag,

Figure 4 is a fourth step, showing the plunger removed and the hat temporarily withdrawn from the mold,

Figure 5 shows the fifth or concluding step, that is, the hat reapplied to the mold and pressure admitted to the interior of the flexible bag, and

Figure 6 discloses the general appearance of the hat body after the several steps of the process have been performed.

In carrying out my process I first take the rough hat body and apply to a surface thereof, for a brief interval, vapor or moistened warm air. This slightly raises the temperature of the body and coats the surface thereof with an ex-

tremely light film of moisture, sufficient only to relieve brittleness. The body is then applied to a heated mold of the shape and size the finished hat is to assume, whereupon a plunger equipped 5 with an expandible head moves into the hat body. Fluid pressure applied to the interior of the head expands the latter and forces the body into intimate contact with the interior of the mold. The temperature of the mold is such as not to convert 10 the film of moisture to steam, but only to vaporize it, and the pressure within the head is sufficient to cause this vapor to entirely penetrate or to be driven through the thickness of the hat body. This permeation of the felt body 15 by the vapor creates a suppleness sufficient only to assure a proper fitting and shaping of the body without disturbing the fur or in any way affecting the color thereof. The pressure is maintained for a few moments, or only sufficiently long to 20 drive the vapor through the body, whereupon it is relieved and the plunger withdrawn. The hat is removed from the mold to the open air for a brief interval, then it is replaced in the mold, the plunger is lowered and pressure again applied. 25 The pressure on this second occasion is continued a trifle longer than in the first instance to definitely fix the size and shape and upon withdrawal of the plunger the hat is removed, the brim is cut and trimmed, lining and 30 sweat bands are applied and the hat is ready for use.

In the drawing 10 indicates a pan or shallow tray mounted upon a suitable support and containing water. A burner 11 beneath the pan supplies 35 sufficient heat to create a vapor rising from the pan through a lattice or foraminous cover 12 on the pan and upon which the rough hat body 13 rests.

The shaping mold is indicated at 14, and is formed preferably of aluminum or other metal 40 having a low coefficient of expansion and of a size and shape the finished hat is to assume. This mold may be suitably supported as shown and is heated in any preferred manner. In the present instance, a gas burner 15 supplies heat to the 45 bottom of the mold while perforated gas pipes 16 supply heat to the upper or brim portions of mold. The mold is equipped with an outstanding flange 17 upon which the brim of the hat will be shaped. 50 The plunger includes the hollow core 18 open at its lower end and which carries a flexible covering 19 of heavy rubber or the like; this cover constituting a bag securely sealed at its upper end 55 in any approved manner upon the exterior of the plunger. This plunger also includes flange pressing portions 20 heated by perforated gas pipes represented at 21. Hydraulic pressure within the plunger is supplied by pipes 22 leading to a suitable 60 source of hydraulic supply and controlled by suitable valves, not shown.

In Figure 1 of the drawing the hat body 13 is shown in the course of the vapor treatment, the vapor passing within the hat body and covering the interior surface only in a light film. The 65 body remains over the pan 10 only for a brief interval, as it is important that the body not be saturated with moisture. In Figure 2 the hat body has been inverted and dropped into the shaping mold 14 and is ready for the first pressure 70 operation. In Figure 3 the plunger has been moved into the mold and hydraulic pressure has been admitted to the interior of the hat, expanding the rubber bag against the hat body and into intimate contact with the interior of the 75 mold. It will be noted that in this position the

outstanding brim of the body is being pressed between the flanges 17 and 20 so that the brim is treated simultaneously with the crown.

In Figure 4 the hydraulic pressure has been relieved, the plunger withdrawn and the hat removed temporarily, while in Figure 5 the hat has been reapplied to the mold, the plunger lowered and hydraulic pressure again applied. Figure 6 shows the appearance of the hat after this last application of pressure.

While no means are disclosed for moving the plunger, it will be understood that the same is brought down with sufficient force to have the parts assume proper position and to create sufficient pressure between the flanges 17-20 to properly treat the brim. As regards internal pressures in the mold, experiments have disclosed that a head of 100 pound pressure produces the best results. The first application of pressure is maintained only for a few moments, just sufficient to vaporize the film and to drive the vapor into the body, and when the hat is withdrawn after this first pressure application, the vapors therefrom rapidly pass off. These vapors are created by the heat from the walls of the mold 14, such heat being sufficient to produce vapor but not steam. By submitting the hat body to a high degree of pressure at the same time the body is heated by the mold, the vapors upon the interior of the hat crown pass entirely through the same and thus sufficiently soften the fibers to obtain a proper and even shaping of the body without disturbing the felt formation or in any way affecting the dye that is present in the body. The momentary withdrawal of the body from the 35 mold brings the hat into the atmosphere and relieves the vapors, and in the second application of the body to the mold, the body is practically dry and substantially free from all moisture. The final pressing operation drives off any remaining 40 moisture and causes the crown and brim to become firmly set and in such condition as to maintain its shape without further treatment.

It has been found that by making the hat in accordance with the method outlined, a number 45 of steps employed in hat treatment methods heretofore proposed are eliminated, and the resulting article is superior to that produced by methods heretofore practiced. The elimination of such steps and the machinery necessary in their 50 performance greatly economizes manufacturing costs in the production of high quality felt hats.

I claim:

1. The method of making felt hats which consists in slightly moistening the surface only of the 55 hat body, thereafter introducing the hat body to a heated mold and applying pressure upon the hat body against the mold.

2. The method of making felt hats which consists in slightly moistening one surface only of 60 the hat body, applying the body to a heated mold with its dry surface against said mold, and driving the moisture through the hat body by applying pressure to the moist surface thereof.

3. The method of making felt hats which consists in slightly moistening one surface only of 65 the hat body, applying the body to a mold heated only sufficient to produce vapor from said moisture, and driving said vapor through the hat body by pressure.

4. The method of making felt hats which consists in slightly moistening one surface only of the 70 hat body, applying the body to a heated mold, applying pressure to the body within the mold for a brief interval, removing the body from the mold, 75

again applying the body to the mold, again applying pressure to the body within the mold, and removing the body.

5. The method of making felt hats which consists in coating a surface only of the hat body with a light film of moisture, applying the body to a mold heated to a degree only to vaporize the

moisture, applying pressure to the body to force the same against the heated mold, withdrawing the body from the mold momentarily, again applying the body to the mold, repeating the pressure upon said body against the mold and finally 5 removing the body from the mold.

SAMUEL KANNER.
